W. B. FAY.
LIFTING JACK,
APPLICATION FILED APR. 3, 1919.

Patented Mar. 16, 1920.

INVENTOR
W. B. Fay
BY John H. Deemers
ATTORNEY

UNITED STATES PATENT OFFICE.

WILLIAM BROWN FAY, OF CHICOOEE FALLS, MASSACHUSETTS, ASSIGNOR TO FAY MANUFACTURING CORPORATION, OF NEW YORK, N. Y., A CORPORATION OF DELAWARE.

LIFTING-JACK.

1,333,966.

Specification of Letters Patent. Patented Mar. 16, 1920.

Application filed April 3, 1919. Serial No. 287,350.

To all whom it may concern:

Be it known that I, WILLIAM BROWN FAY, a citizen of the United States, and resident of Chicopee Falls, county of Hampden, and State of Massachusetts, have invented certain new and useful Improvements in Lifting-Jacks, of which the following is a specification.

This invention relates to lifting-jacks of the character adapted especially for compressing the spring of a puppet-valve of an automobile motor when it is desired to release the valve from its seat for purposes of fitting and grinding.

The principal object of the invention is to provide a compact, readily operable device of the character named which may be successfully operated within the small space between the motor cylinders and the crank case of an automobile, and which is simple in construction, durable, inexpensive and possessed of considerable lifting power.

The device comprises a forked lifting-rod, a forked base-rod, rocking means for connecting said rods and means for locking them in fixed relative arrangement, all as hereinafter fully described and specifically set forth in the annexed claims.

In the accompanying drawings forming part of this specification, Figure 1 is a side view of my improved jack showing the same in operative position and correlation with a puppet-valve stem. Fig. 2 is a plan view. Fig. 3 is a cross sectional view taken on the line 3—3 of Fig. 1; and Fig. 4 is an end view of a clamping link for locking the arms of the device together.

In the example of my invention illustrated by the drawings, A, indicates a lifting-rod embodying the flattened, tapered and forked inner end part 1 and the elongated handle-extension 2; and B, indicates a base-rod embodying a similar forked part 3 and an elongated handle-extension 4. Said rods A and B, are hinged together at a point near their forked parts by means of a rock-link comprising a segmental plate C, which engages oppositely located recesses a and b of the rods A and B, and is secured by means of the fixed pins c and d. It is noteworthy that the hole e, through which the pin d passes, is of larger diameter than the pin, which allows for slight backward or forward movement of the lifting rod to

obviate liability of having the crotch of the 55 fork jam against the puppet-valve stem when the device is being operated.

As a means for locking the extensions 2 and 4, of the rods A and B together, for maintaining the forked parts in spread condition illustrated by full lines Fig. 1 of the drawings, I employ a double link D, which is in pivotal relation with the free end of the extension 4, of the rod B, and embodies the two link-sections f and g. When the 60 forks 1 and 3 are spread apart to their fullest extent as shown by Fig. 1 of the drawings the section f, is swung over the lug h, of the extension 2; and when it is desired to lock the parts in an intermediate 65 position the section g, is used in like manner.

The rods, A and B and the rock-link C, are composed of steel, preferably drop forged, whereby I provide a very strong 75 and durable device adapted to be manually operated for lifting various articles or parts of any mechanism which may require lifting.

In the operation, and use of the device 80 the fork 3 is placed in contact with and caused to bear upon a suitable base, as the screw-head 5 of the screw 6, forming part of an ordinary puppet-valve operating mechanism, not necessary to herein show or 85 describe as it will be well understood by those familiar with the art of motor construction and forms no part of my invention. The free ends of the rods A and B are then moved toward each other by forcing the handle-extension 2 downwardly 90 until the movement causes the fork 1 to contact with and lift the object to be lifted, as the washer 7, surrounding the valve stem 8 and bearing against the coil spring 9, which 95 is located between said washer and the puppet-head 10. The handle parts of the rods are then clamped together by means of the link D, and the forks are maintained in spread relation admitting of easy removal 100 of the key 11, whereby the valve stem and its connected valve may be readily removed, the jack remaining in position for any required time, or until the valve, stem and key are replaced when it is simply necessary to 105 swing the link D, downwardly and allow the spring 9, to exert its pressure on the washer 7. The same operation may be employed

for lifting any mechanism or parts of mechanism or any object which it may be desirable to lift and maintain in lifted position for an arbitrarily selected time.

Having thus described my invention, what I claim as new, and desire to secure by Letters Patent, is:

1. A lifting-jack comprising a lifting-rod embodying a tapered and forked part and a handle-part, and having a recess in its lower side, and a base-rod embodying a tapered and forked part and a handle-part, and having a recess in its upper side; and a rock-link in pivotal connection within said recesses and connecting said rods whereby they may have swinging and forward and backward movement.

2. In a lifting-jack, the combination of a forked and handled lifting-rod, and a forked and handled base-rod, and pivotal means connecting said rods whereby their forked parts may be spread; with clamping means for locking the handle parts together

when the forked parts are in spread condition.

3. In a lifting-jack, the combination, of a lifting-rod embodying a tapered and forked part and a handle-part, and having a recess in its lower side; and a base-rod embodying a tapered and forked part and a handle-part, and having a recess in its upper side, and a rock-link in engagement with said recesses and held by means of two fixed pins, whereby the rods may have swinging and forward and backward movement; with clamping means for locking the said handle-parts together, said clamping means embodying a double link.

In testimony that, I claim the foregoing as my invention, I have signed my name in presence of two witnesses, this 19th day of March, 1919.

WILLIAM BROWN FAY.

Witnesses:

S. G. CONKLING,
A. LENALIE.
